MACHINE FOR PACKAGING CYLINDRICAL
OBJECTS

George B. Holmes, 330 Victory Ave., South San Francisco, Calif.; Charles H. Sinclair, 1817 Hall Ave., Charlotte, N.C.; Perry L. Alexander, Jr., Rte. 4, Matthews, N.C.; and Roy L. Vernon, 305 N. Poplar St., Charlotte, N.C.

Filed Feb. 4, 1957, Ser. No. 637,944
10 Claims. (Cl. 53—32)

This invention relates to a packaging machine and more particularly to a machine for automatically packaging cylindrical articles such as cans of beverage in open-ended cartons while continuously moving the cans and cartons in a forward direction.

Heretofore, most machines for packaging cylindrical objects or cans in cartons have operated intermittently, that is, the carton blank or partially assembled carton remains stationary while groups of cylindrical objects or cans are moved into engagement therewith from above or below or from one of its ends. Needless to say, this stopping of the carton blank or partially assembled carton to receive the cylindrical objects or cans necessarily prevented the packaging machine from being operated at a high speed for great efficiency.

It is therefore the primary object of this invention to provide a packaging machine for cylindrical objects such as cans wherein the cans and carton blanks are continuously moved in a forward direction and the cans received on the carton blank and the carton blank subsequently folded around the cans and sealed to confine the cans therein.

It is a more specific object of the invention to continuously feed carton blanks in spaced apart relation from one elevation and to continuously feed inverted groups of cans from a higher elevation and to move the carton blanks and groups of cans forwardly to a station where the groups of cans are moved onto the moving carton blanks after which each of the blanks is folded laterally around the group of cans and its opposite ends adhesively secured together to complete the package.

It is also an object of this invention to provide a packaging machine adapted to use strip like carton blanks having can locking tabs formed therein and wherein the packaging machine is provided with means for positioning the locking tabs to engage the ends or rim portions of the cans in the carton to prevent their being displaced therefrom.

It is another object of the invention to provide novel means for dividing the cans into predetermined groups while continuously feeding the cans forwardly to the carton blank loading station.

It is a further object of the invention to provide novel means for feeding and delivering the carton blanks to the can loading station.

It is also a further object to provide means for exerting a side pressure or squeezing action to the filled cartons to position the ends or rims of the cans in apertures in the carton formed adjacent the junctures of its side walls and top and bottom walls. This squeezing action also serves to move the opposite ends or flaps of the cartons inwardly towards each other to permit the flaps to be adhesively secured together while the carton is in a tensioned condition.

It is another object of the invention to provide novel overhead compression means to exert a downward pressure on the adhesively secured together carton flaps while the glue is setting and before the carton is discharged from the machine.

It is a still further object of the invention to provide can and carton blank feed safety switches to automatically

2

stop the delivery of the cans and carton blanks upon either becoming exhausted and to provide in conjunction therewith manually operable switches to override the safety switches to permit the machine to be hand controlled as when clearing the machine of cans and carton blanks or when starting up the machine.

Some of the objects of the invention having been stated, other objects will appear as the description proceeds, when taken in connection with the accompanying drawings, in which—

FIGURE 1 is a side elevation of the packaging machine with suitable legend being applied to show the various stages or the points at which various operations occur throughout the machine;

FIGURE 2 is an enlarged fragmentary vertical section taken along line 2—2 of FIGURE 1 but omitting the can actuated control switches;

FIGURE 3 is a schematic partially exploded view showing the drive arrangement for the various stages of the packaging machine;

FIGURE 4 is a schematic elevation showing the manner in which the carton blanks are fed upwardly from below the groups of cans in timed relation thereto to receive the cans while both the carton blanks and cans are continuously moving in a forward direction;

FIGURES 5 and 5-A collectively are a plan view on an enlarged scale of the entire packaging machine with FIGURE 5 showing the rear portion of the machine and FIGURE 5-A showing the front portion;

FIGURE 6 is a front elevation on an enlarged scale looking from the right side of FIGURE 1;

FIGURE 7 is a longitudinal horizontal section on an enlarged scale taken along line 7—7 of FIGURE 1 and showing the arrangement of the various motors in the lower portion of the framework;

FIGURE 8 is a vertical section on an enlarged scale taken along line 8—8 in FIGURE 1 adjacent the rear end of the packaging machine;

FIGURE 9 is a vertical section with parts broken away taken along line 9—9 of FIGURE 8 and showing the feeding means for moving the carton blanks upwardly in spaced apart relation to receive groups of cans thereon;

FIGURE 10 is a longitudinal sectional plan view taken along line 10—10 of FIGURE 9 and showing in detail the carton blank feeding conveyor and the mechanism for positioning the carton blank locking tabs to overlie the wall of the blank on which the cans are received;

FIGURES 11 and 11-A collectively are a vertical section on an enlarged scale taken along line Y—Y of FIGURE 5 with FIGURE 11 showing the rear portion of the machine and FIGURE 11-A showing an intermediate portion and both collectively showing the means for elevating the stack of carton blanks and for feeding the carton blanks upwardly and forwardly to receive the cans thereon and the gluing for the carton blanks;

FIGURE 12 is an enlarged longitudinal vertical sectional view taken collectively on lines A—A and B—B of FIGURES 5 and 5-A and showing the carton folding station, side compression unit, and a portion of the overhead compression unit for sealing the carton;

FIGURE 13 is a transverse vertical sectional view taken along line 13—13 in FIGURE 11-A with the side and overhead compression station not shown for purposes of clarity and showing the station at which the carton blank receives the cans thereon and also showing the gluing station;

FIGURE 14 is an enlarged fragmentary vertical sectional view taken along line 14—14 of FIGURE 13 and showing the gluing station;

FIGURE 15 is a transverse vertical section taken along the line 15—15 of FIGURE 12 and clearly showing the

carton blank folding station and the relationship of the side compression unit thereto;

FIGURE 16 is an enlarged vertical section taken along line 16-16 of FIGURE 5 and showing the means for actuating the fingers or punches for moving the carton locking tabs into a vertical plane;

FIGURE 17 is a horizontal section taken along line 17-17 of FIGURE 16;

FIGURE 18 is an enlarged longitudinal horizontal section taken along line 18-18 of FIGURE 1 and showing the side compression unit for moving the opposite side walls of the carton into tight engagement with the cans to be confined therein;

FIGURE 19 is an enlarged fragmentary plan view looking in the direction of the arrow 19 of FIGURE 1;

FIGURE 20 is an enlarged view of the article or can feeding conveyor looking at the medial portion of FIGURE 2 and showing the can actuated control switches;

FIGURE 21 is an enlarged detail of the stack raising control switch taken along line 21-21 of FIGURE 8;

FIGURE 22 is enlarged detail of the vacuum control switch taken along line 22-22 of FIGURE 2;

FIGURE 23 is an enlarged detail of the solenoid controlled vacuum breaking mechanism taken along line 23-23 of FIGURE 5;

FIGURE 24 is a perspective view of the assembled open ended carton with the carton having been inverted to upright position after being removed from the machine;

FIGURE 25 is a schematic wiring circuit for the machine;

FIGURES 26 to 32 taken in sequence illustrate diagrammatically the various operations performed on the carton blank by the packaging machine to form the carton and to position cans of beverage therein.

Framework

Referring more particularly to FIGURES 1, 3, 6 and 7, an upright substantially rectangular shaped frame is provided, broadly designated at 10. The base of the frame has substantially L-shaped longitudinally extending side members 12 and 12' and longitudinally extending substantially channel shaped inner members 13, 13'. The longitudinally extending base members 12, 12' and 13, 13' rest upon four cross bars 14 suitably secured thereto as by welding.

As best shown in FIGURES 1 and 3, a base plate 15 is supported by the longitudinally extending members at the rear end of the machine. The base plate 15 serves as a platform on which are mounted the several motors and gear boxes of the machine. A cut-out portion 15a is provided in the plate 15 (FIGURE 7) through which extends operating mechanism to be later explained in detail. The forward end of the machine has a relatively small base plate 16 which also rests upon the longitudinally extending base members 12, 12' and 13, 13', with the base plate 16 serving to support bearings which form a part of the drive of the machine.

Extending to the full height of the machine at the rear end are vertical posts 18 and 18' which are suitably secured at their lowermost ends to the longitudinal frame members 12 and 12' and rest upon the rearmost cross bar 14. A transverse bridging member 19 (FIGURE 8) is secured to the uppermost ends of the vertical posts 18 and 18' and forms therewith a rectangular framework.

At the foremost edge of the base plate 15, FIGURE 1, a transverse vertically disposed plate member 20 is provided. The transverse plate 20 as best shown in FIGURE 13, has a cut-out portion 20a formed in the medial portion of its uppermost edge in which rests the frame members of a conveyor unit, to be later described. Also, as viewed in FIGURE 13, a cut-out portion 20b is provided in the upper left-hand corner of the plate 20 for the reception of a glue applying apparatus to be later described. A cut-out portion 20c, FIGURES 1 and 11A, is also provided in the lower portion of the transverse

plate 20 for the reception of the main conveyor and compression drive chains to be later described. Intermediate the base plates 15 and 16 is another transverse vertically arranged plate 21 (FIGURES 1 and 12) having a cut-out portion 21a (FIGURE 15) in the medial portion of its upper end for the reception of the framework of the conveyor unit and a cut-out portion 21b (FIGURE 1) in its lowermost edge for the reception of the compression unit drive chain.

Again referring to FIGURE 1, it will be seen that the machine has a forward transverse vertical plate member 22, having a cut-out portion 22a for the reception of the compression unit drive chain and which is best shown in FIGURE 6. It should be noted that the transverse vertical plate member 22 is of a smaller height than the transverse vertical members 20 and 21.

Extending longitudinally of the machine are relatively large channel-shaped side frame members 24 and 24' which are fastened as by welding to the vertical posts 18 and 18' at the rear of the machine and also to the transverse vertical plates 20, 21 and 22. Forwardly of the transverse vertical plate 21, and resting upon the side frame members 24, 24' is secured as by welding a relatively small platform 26. Another platform 27 is provided forwardly of the platform 26 and in the same plane therewith. The platform 27 is securely fastened to the upper edges of the side frame members 24 and 24' and has a cut-out portion 27a (FIGURE 5A) through which extends part of the chain drive of the compression unit.

Disposed at a higher elevation than the side frame members 24, 24' and extending longitudinally of the machine are relatively small channel-shaped side frame members 28 and 28' (FIGURES 2 and 8) which are securely fastened as by welding to the sides of upright posts 18 and 18' and the transverse vertical plates 20 and 21 with their forward ends terminating at the vertical plate 21. Intermediate the vertical posts 18, 18' and the vertical plate 20, are positioned relatively small pairs of channel-shaped vertical posts 29, 29' (FIGURES 1 and 10) which are securely fastened to the upper edges of the side frame members 24, 24' and the lowermost edges of the small side frame members 28 and 28'. The posts 29, 29' serve as supports to which parts of the inner construction of the machine are secured. Relatively large vertical posts 30 and 30', also extend between the side frame members 24, 24' and the upper side frame members 28, 28' and serve as a support for the bearings of the main conveyor, to be later described.

Immediately above the transverse vertical plate 20, FIGURE 13) are vertically extending posts 32, 32' which are fastened at their lowermost ends to the side frame members 28, 28'. The vertical posts 32, 32' are bridged at their uppermost ends by a transverse frame member 33. A longitudinal brace 34 (FIGURES 11 and 11A) spans the distance between the transverse members 19 and 33 to add rigidity to the frame. As best shown in FIGURES 1 and 15, the machine has short vertical posts 35, 35' having their lower ends suitably secured to the platform 26. The vertical posts 35, 35' are spaced inwardly from the sides of the machine and serve as supports for the rearward end of the overhead carton compression unit to be described in detail later. Longitudinally extending frame members 36, 36' (FIGURES 1 and 5A) extend rearwardly from the vertical posts 35, 35' and have their rear ends suitably secured to the transverse frame member 33. On the rear portion of the platform 27 are mounted vertical posts 37, 37' which with the vertical posts 35, 35' form supports for the overhead compression unit.

Drive means for main shaft

Referring to FIGURES 3 and 7, and more especially to FIGURE 3, it will best be understood the manner in which the various machine parts are driven. A main drive motor 40 is provided having a built in gear box 41 and

a crank handle 42 for varying the speed of the motor 40. The motor 40 is of the type manufactured by U.S. Electric Motors, Inc., Los Angeles, California, and known as a varidrive motor. An endless belt 43 partially encircles a pulley 44 on the forward end of the gear box 41 and imparts rotation to a relatively large pulley 45 mounted on the rear end of a gear box 46, the gear 46 being of the reduction type, and having a sprocket gear 49 mounted on its outside, about which an endless chain 48 extends longitudinally of the machine and passes around a sprocket gear 50 loosely mounted on a main drive shaft 51.

The gear 50 is provided with a collar or hub 52 which bears against a safety clutch collar 53 which is slidably keyed to the shaft 51 and is held in engagement with the collar 52 by a compression spring 54. Suitable pins are secured in the collar 52 which are normally held in indentations in the inner surface of the clutch collar 53, by the spring 54 for driving the shaft 51. Although a specific type of clutch has been described, various other types of clutches could be substituted therefor to function equally as well.

Upon any mechanical failure of the machine or in case the machine should become jammed and overload the main drive shaft, the pins in the collar 52 would ride out of the engagement with the indentations in the clutch collar 53 forcing the clutch collar 53 to move outwardly at which time a plate 56 mounted integral with the clutch collar 53 would bear against a normally closed switch 55 to break the circuit to the electric motor 40, thereby stopping the main drive shaft 51 and the operation of the machine.

Drive means for carton delivery conveyor

The main drive shaft 51 as best shown in FIGURE 7 is journaled in bearings 60 and 61 mounted upon the platform or base plate 15. Adjacent the bearing block 61 is a sprocket gear 63 keyed to the shaft 51 which gear drives a vertically disposed chain 62 (FIGURE 3) having its upper reach partially encircling a sprocket gear 64 mounted on a shaft 66 which is journaled in suitable bearings in the upper portion of the frame of the machine. The shaft 66 serves as the support for the rear end of the main conveyor belt.

Shaft 66 (FIGURE 10) extends transversely of the machine and has relatively large sprocket gears 65 and 65' keyed thereto, the gears 65 and 65' being adjacent or straddling the rearmost end of the main conveyor belt. Spaced apart carton blank delivery chains 67 and 67' partially encircle the sprocket gears 65 and 65' and extend rearwardly and downwardly at an angle to where they partially encircle sprocket gears 68 and 68' keyed on a shaft 70 which is journaled in bearings 70a and 70a' supported on the upper flange of the longitudinal side frame members 24 and 24'.

Drive means for carton blank suction feed

A sprocket gear 71 (FIGURES 3 and 10) is keyed to the shaft 70 about which a sprocket chain 72 is positioned which extends upwardly and rearwardly to a sprocket gear 73 (FIGURES 2 and 3) keyed to a shaft 74 which has one end journaled in a bearing 76 mounted on the longitudinal frame member 28' and its other end journaled in a small bearing 77 mounted on the side of the can delivery conveyor to be later described. The shaft 74 imparts movement to the carton blank suction feed to be later described.

Drive means for chimelock punch

Immediately adjacent the bearing 70a' for the shaft 70 is a sprocket gear 78 (FIGURES 3 and 10) which is engaged by an endless chain 79 for imparting rotation to a small gear 80 keyed on a shaft 83 mounted for rotation in bearings 81 and 81', the bearings 81 and 81' being secured on a plate 82 on the upper edge of the side frame member 24'. The shaft 83 imparts movement to a punch

mechanism illustrated in FIGURE 19 for positioning the locking tabs of the carton in proper locking position which will be described in detail later.

Drive means for can or article delivery chains

Referring to FIGURES 3, 5 and 6, it will be seen that a relatively large sprocket gear 85 is mounted on the main drive shaft 51 outside and adjacent the side frame member 24' about which an endless chain 86 is engaged and extends upwardly for imparting rotation to a shaft 87 through a small sprocket gear 88. The shaft 87 is mounted in bearings 89 and 89' which in turn are mounted on the transverse frame member 33 as shown best in FIGURE 5.

Between the bearing blocks 89 and 89' are bevel gears 92 and 92' (FIGURES 3 and 5) which are keyed to the shaft 87 and impart rotation to mating bevel gears 93 and 93' keyed to the upper ends of vertical shafts 94 and 94' (FIGURE 13). The shafts 94 and 94' are journaled in posts 94a and 94a' which have their upper ends secured to the transverse frame member 33. The vertical shafts 94 and 94' have keyed at their lowermost ends sprocket gears 95 and 95'. Can or article delivery chains 100, 100' partially encircle the sprocket gears 95 and 95' and extend rearwardly around sprocket gears 96 and 96'. The sprocket gears 96 and 96' (FIGURE 5) are mounted on vertical shafts 97 and 97' which are journaled in adjustable bearing blocks 98 and 98' for applying the proper tension to the can delivery chains 100 and 100'. The delivery chains 100 and 100' as will be observed in FIGURES 3 and 5 are positioned on opposite sides of a can delivery conveyor 150 and serve to move the cans C in groups which will be explained in detail later.

As is best shown in FIGURE 5, the sprocket wheels 96 and 96' are positioned a greater distance apart than the sprocket gears 95 and 95' to permit the chains 100 and 100' to operate in a forwardly converging path of travel. Idler sprockets 101 and 101' and 101a, 101a' guide the medial portions of the chains 100 and 100' in their path of travel.

The can delivery chains 100 and 100' have secured on their outer periphery can separation blocks or lugs 102 and 102'. As shown in FIGURE 5, the delivery chain 100 moves in a clockwise direction and the can delivery chain 100' moves in a counterclockwise direction to deliver cans in groups from the rear of the machine to the front. The sprocket gears 96 and 96' by being spaced a predetermined distance from the sides of the can delivery conveyor 150 enable the lugs 102 and 102' to engage the cans at an angle immediately before the chains 100, 100' travel over the idler sprockets 101 and 101' which are positioned closer to the sides of the conveyor 150. The angular or diverging movement of the chains 100 and 100' allows the lugs 102 and 102' (FIGURE 5) to penetrate the solid row of cans C on the conveyor 150 to separate the cans C into groups of six, there being three cans positioned between each of the lugs 102 and three cans between the lugs 102'. The chains now deliver the groups of cans C forwardly beyond the conveyor 150 and onto a stationary track. Upon the lugs 102, 102' passing the respective idler sprockets 101a and 101a', the chains diverge while positioning the groups of cans onto a carton blank B.

Drive means for carton side compression chains

Referring to FIGURES 3, 5 and 12, it will be seen that the bevel gears 93, 93' mesh with bevel gears 105 and 105' which are keyed on longitudinally extending shafts 106, 106' journaled in pairs of bearings 107 and 107', 108 and 108', 109 and 109', which are secured to the longitudinally extending frame members 36 and 36'. The front ends of the longitudinal shafts 106 and 106' have corresponding bevel gears 110 and 110' which mesh with bevel gears 111 and 111' keyed to vertically extending shafts 112 and 112' journaled in bearings 113 and 113' carried by the longitudinal frame members 36.

and 36'. Keyed to the lowermost ends of the vertical shafts 112 and 112' are sprockets 115 and 115', each having a multiple sprocket race for the reception of side pressure applying chains 116 and 116', there being two sprocket chains 116 and two sprocket chains 116' encircling the sprockets 115 and 115' respectively. The side pressure applying chains 116 and 116' extend rearwardly and longitudinally of the machine around idler sprockets 117 and 117' which are keyed on the lower end of vertical shafts 118 and 118' which are journaled in pairs of bearings 119 and 119' supported by the longitudinally extending frame members 36 and 36'.

Drive means for main conveyor belt and overhead compression unit

Referring to FIGURES 3 and 7, a sprocket gear 125 is keyed to the main drive shaft 51 and drives a relatively long endless chain 126 which extends longitudinally and forwardly of the machine to drive a sprocket gear 127 keyed to a shaft 128 which is journaled at its ends in bearings 129 and 129' (FIGURE 6) on the base platform 16. It will be noted from FIGURE 1 that the sprocket chain 126 extends forwardly from the sprocket gear 125 through the opening 20c in the transverse plate 20 and through the opening 21b and 22a of the transverse plates 21 and 22.

A sprocket gear 130 (FIGURES 3 and 6) is keyed to the shaft 128 and drives a chain 131 which rotates a shaft 133 through a sprocket gear 132 suitably keyed thereto. The shaft 133 is mounted in bearings 134 and 134' carried by the upper platform 27. A sprocket 136 is keyed to the shaft 133 and drives an endless main conveyor broadly designated at 135. The innermost end of the main conveyor 135 partially encircles a sprocket 137 (FIGURES 3 and 10) which is loosely mounted on the shaft 66 between the carton delivery chains 67 and 67'.

It will be seen from FIGURE 3 that the main conveyor belt 135 is driven in a clockwise direction and that the overhead compression unit broadly indicated by 142 is driven in a counterclockwise direction. To accomplish this, suitable change gears are provided, there being a gear 133a (FIGURES 3 and 5A) keyed to the shaft 133 which meshes with a gear 134a keyed to a stub shaft 134b, which is mounted for rotation in a bearing 134c attached to the upper platform 27. The stub shaft 134b has a sprocket gear 138 keyed thereon adjacent the bearing 134c on the inner end of the stub shaft 134b opposite the gear 134a. The sprocket gear 138 drives an endless belt 139 for imparting rotation to a sprocket gear 140 (FIGURES 3 and 6) mounted on a shaft 141 which in turn drives the overhead compression unit 142 through a gear 143 keyed to the shaft 141 and mounted in bearings 144 and 144' carried by side frame members of the overhead compression unit to be later described in detail.

Article or can delivery conveyor and drive

Referring to FIGURES 3, 5, 7, 8 and 20, the can or article delivery conveyor broadly designated at 150 comprises four chains 426 driven by sprocket gears 425 mounted on a shaft 152 extending transversely of the machine and being mounted for rotation in bearing blocks 153, 153' and 154 (FIGURE 5). The outer end of the endless article delivery conveyor 150 (FIGURE 4) partially encircles corresponding idler sprocket 425a mounted on a suitably supported shaft (not shown). As will be observed in FIGURE 5, the bearing blocks 153 and 153' are mounted on a plate 153a suitably mounted on the framework for supporting the delivery conveyor 150 which will be described in detail later. As best shown in FIGURE 5, the bearing blocks 153, 153' are mounted adjacent each side of the article conveyor 150. The shaft 152 has one end terminating outside and adjacent the bearing block 153' and the other end terminates outside the bearing block 154 carried by the side frame member 28.

On the shaft 152 intermediate the bearing block 153 and the bearing block 154 is a sprocket gear 155 (FIGURE 5) about which a sprocket chain 156 is positioned. The sprocket chain 156 extends downwardly from the gear 155 to a large sprocket gear 157 (FIGURES 3 and 7) mounted to the drive shaft of a combination gear box and motor 158.

Conductors 158a and 158b (FIGURE 25) extend from lead conductors 535 and 536, respectively, to the motor 158. A manual switch *b* is interposed in the conductor 158a to permit the operator to start and stop the motor 158. It will be seen from the foregoing description that upon energy being supplied to the motor 158, the article conveyor 150 will operate separately from the other drives of the machine to insure that a continuous supply of articles is fed to the machine at all times.

Drive for gluing apparatus

Referring to FIGURE 11A, an auxiliary motor and gear box 160 having a shaft 161 is provided to drive a gluing mechanism broadly indicated at 170. For manual starting and stopping of the motor and gear box 160, suitable conductors 160b and 160c (FIGURE 25) extend from the lead conductors 535 and 536, respectively, with the conductor 160b having a switch *e*. The motor and gear box 160 is mounted upon a platform 160a, FIGURE 7, which is in turn securely fastened to the side frame member 24'. The gear box shaft 161 has a sprocket gear 162 (FIGURES 7 and 11A) keyed thereto, which drives a chain 163 to drive a double sprocket 164 loosely mounted on the main drive shaft 51. An endless chain 165 extends upwardly from the sprocket 164 and engages a sprocket gear 166 carried on a stub shaft 440 mounted for rotation in the gluing apparatus broadly designated at 170, FIGURES 11A and 13.

Stack or carton blank raising means

Referring to FIGURE 7, it will be seen that the main drive shaft 51 has a cam plate 180 mounted intermediate the sprocket gears 63 and 164, whose periphery engages a cam follower 181 (FIGURES 7 and 11A) on an arm 182 mounted on a stub shaft 183 in a bearing 184 mounted on the base plate 15. The arm 182 is keyed on the shaft 183 for pivotal movement and has a link rod 192 secured to its upper end and extending rearwardly or to the right in FIGURE 11A to where it is fastened to a feed pawl arm 191 (FIGURE 11) of a stack raising mechanism broadly designated at 185.

The stack raising mechanism 185 is best shown in FIGURES 8 and 11 and comprises a ratchet wheel 186 mounted on a stub shaft 187 which is journaled in a bearing bracket 188. The shaft 187 extends through the bearing bracket 188 and has a sprocket gear 190 mounted on its outer end. Mounted between the ratchet wheel 186 and the bearing 188 is a feed pawl arm 191 having a bifurcated upper portion in which is fastened one end of the link rod 192. A feed pawl 193 is pivotally mounted as at 194 to a projection on the feed pawl arm 191, the feed pawl 193 having a tooth engaging finger 195 which engages teeth 196 in the periphery of the ratchet wheel 186.

A brace 197 (FIGURE 11) is fastened to the bearing bracket 188 and has pivoted at 198 in its uppermost end a hold back pawl 200 which normally engages the ratchet wheel 186. It will also be seen from FIGURES 8 and 11 that the feed pawl arm 191 has integral therewith a downwardly extending arm 201, which is at times engaged by a latch member 202 pivotally mounted as at 203 in a bearing stand 204. A link 205 is pivotally secured to a medial portion of the latch member 202 and extends down to a solenoid plunger 206 of a solenoid 207. As shown in FIGURE 11 the solenoid 207 is not energized and the latch member 202 is held in engagement with the lower end of the arm 201 by a tension spring 209 having its opposite ends fastened to the solenoid plunger arm 206 and the brace 197, respectively.

A cable 210 has one end securely fastened to the end of the hold back pawl 200 and its other end to a lever 211. A medial portion of the cable 210 is secured to the end of the feed pawl 193. The lever 211 is keyed to a shaft 212 which extends transversely of the machine and penetrates each of the side frame members 24 and 24' (FIGURE 8). To permit the shaft 212 to be turned, actuating handles 213 and 213' are securely fastened to its outermost ends. Upon rotation of the shaft 212 by one of the handles 213, 213', the feed pawl 193 and hold back pawl 200 will become disengaged from the ratchet wheel 186 through the lifting action of the cable 210, which will permit the elevator station, to be later described, to be lowered. It will be noted in FIGURE 11A that the link arm 182 has a tension spring 215 fastened thereto which extends rearwardly and is fastened to the base plate 15. The tension spring 215 serves to keep the cam follower 181 of the link arm 182 in engagement with the periphery of the cam 180. It should be noted at this point that whenever the solenoid 207 is not energized, and is in the position as shown in FIGURE 11, the latch member 202 bears against the arm 201 to prevent the link rod 192 and arm 182 from moving to the right as viewed in FIGURE 11A, to thus prevent the cam follower 181 from following the low spots of the rotating cam 180.

Referring now to FIGURE 8, it will be seen that the vertical posts 18 and 18' have bearing blocks 217 and 217' respectively mounted at their lowermost ends and bearing blocks 218 and 218' mounted at their uppermost ends in which are journaled upper and lower shafts 219 and 219' respectively. Mounted adjacent and inwardly of the bearing blocks 217 and 218 is a stack raising chain 226, which engages a sprocket gear 221 on the shaft 219', and a sprocket gear 222 on the shaft 219. Mounted adjacent the bearing blocks 217' and 218' is a stack raising chain 220' which partially encircles a sprocket gear 221' on the shaft 219', and a sprocket gear 222' on the shaft 219. Outside of the bearings 218 and 218' on the shaft 219 (FIGURE 8) are fastened hand wheels 219a and 219a', which are adapted to be turned to raise and lower the blank carton elevator station, after the ratchet wheel 186 has been disengaged by the action of the handles 213, 213' previously described.

Adjacent the sprocket gear 221 on the shaft 219' (FIGURES 8 and 11) is a relatively large sprocket gear 223 which is driven by a sprocket chain 224 which in turn is driven by the smaller sprocket gear 190 mounted on the outermost end of the stub shaft 187 carried by the bearing block 188. Fastened to the rearmost reaches of the sprocket chains 220 and 220' are elevator blocks 225 and 225' (FIGURES 8, 10 and 11) which are keyed to ride in vertically extending guide posts 226 and 226'.

The guide posts 226 and 226' are fastened at their lower ends to plates 227, 227' (FIGURE 8) which extend from the rearmost foot member 14. Extending transversely of the machine and securely fastened to the elevator blocks 225 and 225' is an elevator supporting bar 228 (FIGURES 9, 10 and 11) upon whose medial portion is positioned an elevator platform broadly designated at 230. The elevator platform 230 comprises rollers 232 which are journaled at their ends in side frame members 233, 233', and it is upon the rollers 232 that the carton blanks B are positioned. As is best shown in FIGURES 7 and 10, the carton blanks B are positioned upon the elevator platform 230 in the medial portion of the machine. Vertical rising angle bars 234 and 234' having carton blank guide plates 235 and 235' mounted thereon, are fastened at their lower ends to the plates 227 and 227'. The guide plates 235 and 235' are spaced apart exactly the width of the carton blanks B to insure that the carton blanks B are in alinement one above the other at all times to maintain the guide plates 235 and 235' spaced apart a predetermined distance. Suitable transverse bracing rods 236 and 236' extend between the

vertical angle bar members 234, 234' and the vertical guide posts 226 and 226'.

Having shown how the side edges of the carton blanks B are kept in vertical alinement the means for keeping the leading edge of the carton blanks B in vertical alinement will now be described. Suitable vertically disposed carton blank guide plates 240 and 240' are secured to vertically positioned angle bars 241 and 241' (FIGURES 7 and 10) which have their lower ends mounted to the longitudinal frame members 13 and 13'. The angle bars 241, 241' are fastened at their uppermost ends to transverse angle bars 242 and 243 (FIGURES 8 and 10) which extend transversely of the machine and are fastened to the frame posts 18 and 18'.

15 The energizing means for the solenoid 207 will be described later. However, assuming that the solenoid 207 has been energized and the solenoid plunger retracted from the position shown in FIGURE 11 to release the arm 201 which is formed integral with the feed pawl arm 191, the cam follower 181 (FIGURE 11A) will then be permitted to follow the periphery of the cam 180. Upon the cam follower 181 engaging the low portion of the cam 180, the rod 192 will be moved rearwardly to swing the pawl arm 191 rearwardly in a clockwise direction allowing the finger 195 of the feed pawl 193 to ride over the teeth 196 of the ratchet wheel 186. Now, upon the high side of the cam 180 engaging the cam follower 181, a forward motion will be imparted to the rod 192 which in turn will bring the pawl arm 191 forward at which time the finger 195 of the feed pawl 193 will engage one of the teeth 196 of the ratchet wheel 186, imparting rotation to the sprocket wheel 190, the chain 224 and sprocket gear 223, to rotate the shaft 219' in a clockwise direction thereby driving the stack raising chains 220 and 220' to raise the carton blank elevator platform 230. During the rearward stroke of the pawl arm 191, the hold back pawl 200 will engage one of the teeth 196 of the ratchet wheel 186 to hold the carton blank elevator platform stationary.

40 It will be seen from the foregoing description, that the continuous operation of the stack raising mechanism broadly indicated by 185 would deliver the carton blanks B faster than the machine could pick up and deliver the same. For this reason, a control for the stack raising mechanism in the form of the solenoid 207 is provided, the intermittent operation of which will be described shortly.

Carton blank feeding means

50 The carton blank feeding mechanism comprises a plurality of vacuum controlled carton blank grasping or transferring devices shown in the form of resilient suction cups, each of which is designated at 250, there being two of these shown in FIGURES 2 and 8. Each of the suction cups 250 is communicatively connected as by a T connection to one end of a common vacuum line 251 which extends to a vacuum release mechanism broadly indicated by numeral 328 (FIGURE 23) and then to a vacuum pump 256 (FIGURE 7) mounted on the base plate 15. The vacuum pump 256 is provided with a pulley 255 which is driven by a pulley 254 on a motor 252 through a V-belt 253. Suitable conductors 252a and 252b (FIGURE 25) lead from the motor 252 and are connected to the lead conductors 535 and 536. For starting and stopping the motor 252 a manual switch c is interposed on the conductor 252a.

60 The shaft 74 (FIGURE 11), the operation of which has been previously described, has positioned thereon a suction cup lowering and raising cam 260 and a carton blank delivery cam 261. The suction cups 250 are securely fastened to the bottom of a transverse member 262 (FIGURES 2 and 8) which extends between two vertically rising suction cup arms 263 and 263' which are pivotally mounted to crank arms 264 and 264' at 265 and 265' respectively. The crank arms 264 and 264' are suitably keyed to a transverse shaft 266 which is carried by bear-

ings 267 mounted on the upper side of the transverse frame member 19. As shown in FIGURES 8 and 11, the left-hand portion of the transverse shaft 266 has a crank arm 268 mounted thereon. An adjustable L-shaped link 269 is pivoted as at 270 to the lower end of the crank 268, and extends downwardly and forwardly with its lower end being pivotally connected as at 271 to one end of a suction cup raising lever 272.

The suction cup raising lever 272 is pivotally mounted at a medial portion to a stub shaft 273 which is mounted in a bearing 274 secured to the lowermost edge of the longitudinal frame member 28'. The other end of the suction cup raising lever 272 has a cam follower 275 (FIGURE 11) mounted thereon, which engages the periphery of the suction cup raising cam 260. Now, upon the low spot of the suction cup raising cam 260 engaging the cam follower 275, it is apparent that the link 269 will be lowered to rotate the shaft 266 clockwise as viewed in FIGURE 11 to lower the arms 263 and 263' to thus lower the suction cups 250 to a point where they will pick up one of the carton blanks B. As will be observed in FIGURE 11, the point at which the lever 272 is mounted on the stub shaft 273 is closer to the rear end of the lever than its forward end to thus permit the weight of the rear portion of the lever to serve as a biasing means for normally maintaining the cam follower 275 in engagement with the cam 260. To further insure the normal positioning of the cam follower in engagement with the cam 260, a spring 308 is connected to the rear end of the lever 272 to exert a downward pull thereon.

The manner in which the solenoid 207 is controlled by the uppermost positions of the stack of carton blanks B to periodically permit the elevator platform 230 to be raised will now be described. As best shown in FIGURE 21, a switch actuating lever 300 is suitably secured to a collar 301, keyed to the left-hand outermost end of the shaft 266, as viewed in FIGURE 8, with the switch actuating lever 300 having a manual adjustment screw 302 penetrating its outer end portion. The screw 302 can be adjusted to any desired setting to permit the same to strike a switch button 304 of a switch 303 at predetermined intervals. The switch 303 is normally open and when the switch button 304 is depressed electric current will flow through to the solenoid 207. As will be observed in FIGURE 25, a conductor 305 connects the solenoid 207 and one side of the switch 303, and a conductor 306 connects the other side of the switch to the lead conductor 535. To complete the circuit, a conductor 305a connects the solenoid 207 to the lead conductor 536. As stated before, when the solenoid 207 is energized it pulls the latch member 202 (FIGURE 11) downwardly and out of engagement with the lowermost arm 201 of the pawl arm 191 to permit the stack raising mechanism 185 to raise the elevator platform 230 a predetermined amount to a point where a predetermined number of carton blanks B will be in position where they will be successively picked up by the suction cups 250 before the stack raising mechanism 185 is again energized. For purposes of explanation, it is assumed that each time the stack raising mechanism 185 is in operation, the platform 230 is elevated a distance equal to the thickness of five carton blanks.

The carton raising cam 260 has a low and high portion to respectively lower and raise the suction cups 250 to pick up a carton blank B for each revolution of the cam. Now, upon the cam follower 275 approaching the low spot of the cam 260, the suction cups 250 will be lowered to a point where they will pick up the first or uppermost carton blank B. During this operation the cam follower 275 will not engage the low spot of the carton raising cam 260 since the suction cups are not lowered their maximum amount, but are stopped by the uppermost carton blank, to thus through the arms 263, 263', crank arms 264 and 268, and rod 269 cause the rear end of the lever 272 to be elevated. It will be observed in FIGURE 21, that during this picking up of the uppermost carton the switch actuating arm 300 will not engage the switch button 304

of the switch 303 to close the circuit to the solenoid. As each of the next four successive cartons are removed, the cam follower 275 on the suction cup raising and lowering lever 272 will be permitted to move closer and closer to the low spot on the carton raising cam 260, whereby upon the last carton blank of the group being reached, the cam follower 275 will engage the low spot of the cam to permit the switch actuating arm 300 to be thrust against the switch button 304 of the switch 303 to energize the solenoid 207. The latch 202 will then become disengaged from the lowermost arm 201 of the pawl arm 191, at which time the cam follower 181 will follow the cam 180 and operate the carton raising mechanism 185 to raise the stack of carton blanks a distance equal to the thickness of five blanks.

Horizontal carton feeding means

Referring to FIGURES 2, 11 and 22, it will be seen that the horizontal carton feeding cam 261 is keyed to the shaft 74 between the suction cup raising and lowering cam 260 and the article delivery conveyor 150. Mounted rearwardly of the shaft 74 and at a lower level is a transverse shaft 310 suitably journaled in bearings 311 and 311'. The bearing 311 is securely fastened to the bottom of a horizontally disposed U-shaped frame member 312 (FIGURE 2) which is, in turn, securely fastened at its open end to short transverse braces 313 and 313', the brace 313 being secured to the rearmost end of the longitudinal frame member 28 and the side frame of the article conveyor 150, the brace 313' being fastened between the rearmost end of the longitudinal frame member 28' and the opposite side frame member of the article conveyor 150.

As best seen in FIGURES 11 and 22, a cam follower 316 is mounted on one arm of a crank arm 315, the other end of which is keyed to the shaft 310. A substantially vertical crank arm 317 is also keyed to the shaft 310 and has pivotally connected at its outermost end an adjustable link 318 extending horizontally forwardly to where it is pivotally connected to the vertical suction cup supporting arm 263' (FIGURE 11). Upon counterclockwise rotation of the shaft 74, as viewed in FIGURE 11, the horizontal carton delivery cam 261 will be rotated with the high spot of the cam 261 forcing the cam follower 316 downwardly to impart counterclockwise movement to the shaft 310 and its arm 317, whereby the suction cup 250 will be moved in a horizontal direction forwardly at which time the carton blank B, carried by the suction cups 250, will be deposited between rollers to be later described.

As best shown in FIGURE 22, it will be seen that a switch actuating lever 320 is fastened to a collar 321 which is keyed to the shaft 310 at its end remote from the crank arms 315 and 317. An adjustment screw 323 is mounted in the end of the switch actuating lever 320 for manual adjustment. Upon the high spot of the cam 261 having forced the cam follower 316 downwardly, as shown in FIGURE 22, one of the carton blanks B will have been delivered between feed rollers whereupon the suction to the cups 250 is cut off by the adjustment screw 323 engaging a switch button or plunger 324 of a normally open switch 325 which actuates a solenoid valve 328 (FIGURES 23 and 25).

The solenoid valve 328 is mounted on the longitudinal side frame member 24 and is interposed in the vacuum line 251 which leads from the suction cups 250 to the vacuum pump 256. To energize the valve 328, a solenoid coil 329 is provided, one side of which is connected by a conductor 326 (FIGURE 25) leading from the switch 325. A conductor 326a extends from the opposite side of the solenoid coil 329 to a lead conductor 536 in a main control panel 539. Conductor 327 extends from the control panel 539 and lead conductor 535 to the switch 325, to complete the circuit. Suitable conductors 540 and 541 are provided to bypass the switch

325, providing the operator with means for energizing the solenoid coil 329 to break the vacuum to the cups 250. Conductor 540 extends from the lead conductor 535 to the conductor 326 and has a manual switch *a* interposed therein. Conductor 541 communicates with the lead conductor 536 and the conductor 326a. It is thus seen that upon closure of the switch *a*, electrical current will flow through the conductors 540, 326, 326a and 541, completing a circuit to energize a solenoid coil 329.

Now referring to FIGURE 23, a plunger arm 330 extends through the solenoid coil 329 and is connected to a valve core 332 by means of a link 331 therebetween. The valve core 332, is slidably mounted in a bore or chamber 333 of a valve housing 334. A compression spring 335 is positioned between the inner end of the chamber 333 and the valve core 332, to normally force the valve core 332 outwardly against a retaining ring 336 mounted in the valve housing 334. As shown in FIGURE, 22 the solenoid coil 329 is de-energized and the spring 335 has forced the valve core 332 against the retaining ring 336 which permits a bore 337 in the valve core 332 to communicate with a bore 338 and 338' in the valve housing 334 at which time suction will be created in the suction cups 250 by action of the vacuum pump 256.

However, when a carton blank B has been delivered forwardly by the suction cups 250, the switch 325 (FIGURE 25) will then be closed at which time electric current will flow through the wires 326 and 326a to the solenoid valve 328 at which time the solenoid coil 329 will become energized and the valve core 332 through the action of the solenoid plunger 330 will be moved inwardly to compress the spring 335, and open the bores 338 and 338' to the atmosphere. In this position, air from the atmosphere is permitted to flow through an open end 339 of the compartment 333 to the vacuum line 251. The suction cups 250 will then have their vacuum broken to release the carton blank B and deposit the same between feed rollers, to be later described.

Auxiliary carton blank feeding means

The auxiliary carton blank feeding station is best shown in FIGURES 8, 9, 10 and 11. The operation of how the suction cups 250 deliver one of the carton blanks B forwardly of the machine to deposit it between sets of rollers has already been given. It is at this point that the auxiliary carton blank feeding means takes over to move the carton blanks forwardly. The auxiliary carton blank feeding means is broadly designated at 350, and consists mainly of three endless belts 351, 351' and 353, the first two of which encircle pulleys 352 and 352' which are keyed to the shaft 70 and mounted adjacent the outside of the sprocket gears 68 and 68' respectively. The endless belt 353 encircles a pulley 353a, keyed to the shaft 70 at the medial portion of the machine. The endless belts 351, 351' and 353 extend rearwardly of the machine as viewed in FIGURES 9 and 10, at which point they encircle relatively small pulleys 355, 355' and 356, respectively, keyed to a shaft 357 which is journaled in bearings 358 and 358'. The bearings 358 and 358' are mounted on small longitudinally extending plates, the front edges of which are mounted on the transverse frame member 243 with their rearward edges securely fastened to the vertical angle posts 234 and 234'.

Suitable belt tensioning devices are provided for each of the endless belts 351 and 351'. As illustrated in FIGURE 10, the belt tensioning means consists of pulleys 360 and 360' mounted for rotation on the free ends of levers 361 and 361', the other ends of which levers are securely fastened to a relatively short transverse rod 362 which is, in turn, journaled in bearings 363 and 363' mounted on the uppermost edge of the transverse frame member 243. The levers 361 and 361' have tension springs 364 and 364' fastened to their medial por-

tions and extending upwardly therefrom with their uppermost ends securely fastened to the inner ends of braces 365 and 365' which extend inwardly or transversely of the machine (FIGURE 10) and are supported at their outer ends by the upright frame members 18 and 18'. Mounted in vertical alignment with the pulleys 355 and 355' are mating feed wheels 367 and 367' of the same diameter. As best shown in FIGURE 8, the central endless belt 353 does not have a mating feed wheel positioned above its pulley 356 since the belt 353 merely serves as a support for the central portion of the carton blanks B.

Small bearing blocks 368 and 368' are mounted on the lowermost part of the horizontally disposed U-shaped frame 312, and have levers 369 extending rearwardly and downwardly therefrom. The levers 369 and 369' are pivotally mounted in the bearing blocks 368 and 368' and have feed wheels 367 and 367' mounted for rotation in their outermost ends. Compression springs 370, 370' extend between the levers 369 and 369' and the U-shaped plate 312 to normally force the wheels 367 and 367' into engagement with the pulley wheels 355 and 355' to permit a carton blank B delivered by the suction cups 250 to be engaged in the nip between the wheels and thus delivered forwardly.

As best shown in FIGURES 9 and 10, upon clockwise rotation of the shaft 70 by the carton delivery chains 67 and 67', clockwise rotation is also imparted to the endless belts 351, 351' and 353. Any carton blank B positioned between the pulley wheels 355 and 355' and the wheels 367 and 367' will now be delivered forwardly of the machine on the upper reaches of the belts 351, 351' and 353 to a point where the rearmost edge of the carton blank B is in vertical alignment with the shaft 70, at which time blocks 372 and 372' mounted on the periphery of the carton blank delivery chains 67 and 67' will engage the rearmost edge to carry the carton blank forwardly at a slight upward angle to the article or can loading station.

Again referring to FIGURES 9 and 10, it will be seen that the outermost side edges of the carton blanks B will be positioned between longitudinally extending carton blank guide members 373 and 373'. The guide members 373 and 373' are provided with opposed V-shaped recessed portions 373a and 373a' and are so mounted that the edge of the carton blank B will be guided by the innermost walls forming the recessed portions. It should also be noted that the rearmost ends of the guide members 373 and 373a' are flared to provide bell mouthed portions 373b and 373b', which insure that the outermost side edges of the carton blanks B are guided into the V-shaped recessed portions 373a and 373a'. Adjacent each side of the pulley 353a are spaced apart longitudinally extending bars 374 and 374' which serve as guides or supports for the central portion of the carton blank B as it is delivered forwardly of the machine.

It should also be noted at this time that the longitudinal extending bars 374 and 374' have their uppermost surfaces in horizontal alignment with the upper reaches of the carton delivery chains 67 and 67', and that the bars 374 and 374' are supported at their medial portions upon short transverse angular frame members 375 and 375' and a bridging frame member 376. The transverse frame member 375 is in longitudinal alignment with the transverse frame member 375' and is supported at its outer end by the upright channel member 29. The transverse member 375' is supported at its outer end by the opposing upright member 29'. The transverse member 376 bridges the machine and is fastened at its outer ends to other upright channel members 29 and 29'.

Positioned above the longitudinal bars 374 and 374' are longitudinally extending carton hold-down bars 378 and 378' which are the same length as the longitudinal bars 374 and 374' and have their ends positioned in vertical alignment therewith. As will be observed in

FIGURE 10, the rearmost ends of the carton blank hold-down bars 378 and 378' are curved upwardly as at 378a and 378a' and the longitudinal bars 374 and 374' positioned thereunder have their rearmost edges curved downwardly, to insure that the leading edge of the carton blank B will be sandwiched between the upper longitudinal bars 378 and 378' and the lower longitudinal bars 374 and 374' in its path of travel. As best shown in FIGURE 9, a pair of carton blank hold-down wheels 380 (only one of which is shown), are provided above the endless belts 351 and 351' to normally engage a carton blank immediately before it passes into the bell mouth openings 373b and 373b' of the angle guide members 373 and 373'. The hold-down wheels 380 thus serve as guides for the carton blanks by maintaining them in engagement with the belts 351 and 351' during their path of travel. The hold-down wheels 380 and 380' are urged towards the endless belts 351 and 351' by gravity and have link arms 381 and 381' extending forwardly to where they are pivotally secured in bearings 382 and 382' mounted on the underside of the plate 153a. It is thus seen that a carton blank B having been delivered forwardly by the suction cups 258 will then be positioned between the pulley wheels 355 and 355' and the upper wheels 367, 367' at which time the endless belts 351 and 351' and 353 will deliver it forwardly to where its outermost edges will pass between the guide members 373 and 373' and that its central portion will be guided between the lower longitudinal bars 374 and 374' and upper longitudinal bars 378 and 378' and that the blocks 372 and 372' carried by the carton delivery chains 67 and 67' will then engage the rearmost edge of one of the carton blanks B to deliver it forwardly to an article or can receiving station to be explained shortly.

Operation of chime lock punch

Before describing the chime lock punch mechanism which positions pairs of carton locking tabs 387 and 387' in the position shown in FIGURE 28 to receive the articles or cans on the carton blank, a detailed description of the carton blank B follows: It should be stated at this time that the carton blank B is fed into the machine in an inverted manner, and that as viewed in FIGURES 10, 19 and 26 to 28, you are looking at the inside of one of the carton blanks B.

The carton blank B consists of a top wall portion 385 which has two die cut portions 386, which serve as handles in which the fingers may be extended for picking up the filled carton. The chimelock portions or locking tabs 387, 387' are die cut in the top wall portion 385 in the shape of half moons which face inwardly or towards the center of the top of the carton wall 385 and have score lines 388 and 388' at the terminal ends thereof to readily permit the tabs to be subsequently folded inwardly from the position shown in FIGURES 10 and 26 to the position shown in FIGURE 28.

The carton blank B also has side wall portions 390 and 390' which are adapted to be folded upwardly as the carton blank B passes through the machine, the break or fold line between the side portions of the carton B and the top wall portion being designated at 391 and 391'. The top wall portion 385 of the carton blank B is of a narrower width than the two rows of cans to be positioned therein and in order that the side wall portions 390 and 390' may be readily folded upwardly and against the sides of the cans C, die cut portions or lips 392 and 392' are provided in the side wall portions 390 and 390', which portions as will be later described tend to lock the cans C into the carton blank B by forming apertures to receive rim portions of the cans.

The bottom wall portion of the carton blank B is made up of two sections 393 and 394 and as viewed in FIGURE 10, the underside of the bottom section 394 will have glue applied thereto as at 395. Suitable break or score lines 397 and 397' are provided to separate the

side wall portions 390 and 390' from the bottom wall portions 393 and 394, respectively. Die cut portions or lips 398 and 398' are provided in the side panels 390 and 390' to serve the same purpose as the die cut portions 392 and 392', i.e., to form apertures in the side walls to receive rim portions of cans and thus to aid in preventing the cans from being displaced through the open ends of the assembled carton.

Now, referring to FIGURES 9, 10, 16 and 17, keyed to the innermost end of the shaft 83 adjacent the bearing block 81 are two cam supporting disks or wheels 400 and 400' each of which has an arm or cam 401, 401' extending radially therefrom. It will be noted in FIGURE 16 that the cams 401, 401' are spaced approximately 135 degrees apart. In operation, cams 401 and 401' engage cam followers 402 and 402' which are mounted for rotation on the end of a lever 403 which has its other end keyed to a chime lock punch actuating shaft 404, which is journaled in bearings 405 and 405' (FIGURE 10) securely fastened to suitable longitudinal bars that have their foremost ends welded to the top edge of the transverse members 375 and 375'. The shaft 404 extends transversely of the machine and has an extended portion adjacent the bearing block 405' to which a downwardly extending lever 406 is secured which extends at approximately right angles to the lever 403.

A compression spring 407 is secured to the outermost end of the lever or link 406 and has its opposite end fastened to a screw eye 408 mounted in the uppermost side of the plate 82. As is best shown in FIGURE 16, the compression spring 407 forces the cam followers 402, 402' in an arcuate path towards the shaft 83 and towards the cams 401 and 401'. To limit the movement of the lever 403 a resilient headed stop screw 410 is provided which is mounted for manual adjustment in a threaded aperture in a support 411 which is mounted adjacent the bearing block 405'. An adjustment nut 412 is provided to lock the stop screw 410 in the desired adjusted position on the support 411.

Upon clockwise rotation of the shaft 83, as viewed in FIGURES 16 and 17, clockwise rotation will be imparted to the cams 401 and 401', whereupon the cams 401, 401' will engage the cam followers 402 and 402' at intermittent stages to thereby impart counterclockwise rotation to the chime lock punch shaft 404.

Now, referring to FIGURES 10 and 19, in longitudinal alignment with the chime locks or locking tabs 387, 387' of the carton blank B, FIGURE 10, are chime lock punch fingers 415 and 415' which are securely fastened in blocks 417 and 417' secured to the chime lock punch shaft 404. Each of the chime lock punch fingers 415 and 415' have bent up forward end portions 416 and 416' which engage the chime lock portions 387 and 387' of the carton blank B to punch the chime lock portions upwardly from the horizontal position shown in FIGURE 26 to the position shown in FIGURE 27 where the chime lock portions are at an angle of 90 degrees with respect to the top wall portion 385 of the carton blank B.

It is to be distinctly understood at this time that the carton blanks B are delivered in a continuous manner by the carton delivery chains 67 and 67' and that, at the exact moment the forward or first pair of chime lock portions 387 and 387' of the carton blank B are positioned above the bent up portions 416 and 416' of the chime lock punch fingers 415 and 415', that the cam 401' will engage the roller 402' to thereby cause the chime lock shaft 404 to rotate counterclockwise, to thereby cause the bent up portions 416 and 416' to move upwardly and punch up the foremost chime lock portions 387 and 387' of the carton blank B.

As best shown in FIGURE 19, the hold-down bars 378 and 378' have small cut out portions or dies 418 and 418' through which the bent up portions 416 and 416' of the chime lock fingers 415 and 415' extend when punching

the portions 387 and 387' upwardly. Immediately after the first or forward pair of chime lock portions 387 and 387' have been punched up, the chime lock punch fingers 415 and 415' drop downwardly to their normal position below the carton blank B by the action of the tension spring 407 returning the shaft 404 to its normal position upon the cam 401 having moved out of contact with the cam follower 402'. As the carton blank B is moved forwardly, the first pair of chime lock portions 387 and 387' will engage half circular portions 420 and 420' formed integral with the longitudinal bars 378 and 378', to prevent the chime lock portions 387 and 387' from returning to their original horizontal position. As the carton blank B is moved forwardly further, the chime lock portions 387 and 387' will be bent outwardly as they are moved against angular edge surfaces 421 and 421' of the longitudinal bars 378 and 378'. This is best illustrated in FIGURE 19 wherein the forward or first pair of chime lock portions 387 and 387' have already been bent over by the angular edges of the longitudinal bars 378 and 378' to where they will be securely held down and delivered in this manner to a point where the cans C will be deposited upon the carton blank B.

As is apparent upon an inspection of FIGURE 19, the second or rearward pair of chime lock portions 387 and 387' will be moved upwardly into a vertical plane during the outward bending or folding of the first pair of chime lock portions into a position to receive cans. This is accomplished by the positioning of the cam 401 a distance away from the cam 401' corresponding to the distance between the first and second pair of chime locks, so that upon the cam 401 engaging the cam follower 402, the second pair of chime locks will be positioned in the dies 418, 418' to be engaged by the bent up portions 416 and 416' during their upward movement imparted thereto by the counterclockwise movement of the shaft 404.

Article conveyor and guide means

As best shown in FIGURES 8 and 20, the article delivery drive shaft 152 for the article conveyor broadly indicated by reference numeral 150 has four sprocket wheels 425 keyed thereto between the bearing blocks 153 and 153', each of which wheels drive an endless conveyor chain 426. The endless chains 426 pass around other suitably supported sprocket wheels 425a (FIGURE 4) on the rear end of the article conveyor 150. Longitudinally extending side panels, in the form of channel-shaped members 427 and 427' are suitably secured to the upper surface of the rear portion of the horizontally disposed U-shaped plate 312 (FIGURE 9) and extend forwardly and rearwardly thereof to support a plate 428 which supports the chains 426. The plate 428 bridges the side frame members 427 and 427' by engaging their uppermost edges and extends longitudinally of the side frame members 427 and 427' from a point above the sprocket gears 425a (FIGURE 4) and terminating at approximately a point vertically of the drive shaft 66 (FIGURE 9). It is on the upper surface of the longitudinal plate 428 that the upper reaches of the article delivery chains 426 rest for sliding movement thereon.

The upper reaches of the article conveyor chains 426 move in a clockwise direction and having passed around the sprocket gears 425, the chains 426 then ride on the upper surface of a longitudinal lower plate 429 (FIGURE 20) which extends from underneath the sprocket gears 425a to a point approximately under the sprocket gears 425. As best shown in FIGURE 20, the chains 426 are spaced an equal distance apart and the upper reaches thereof have longitudinal bars 430 disposed therebetween, the upper surface of which bars are approximately one-eighth of an inch lower than the upper surfaces of the chains 426. Articles or cans C are delivered forwardly by frictional engagement with the chains during the clockwise rotation of the upper reaches thereof. The chains will at times slide underneath the cans C without impart-

ing movement thereto, as when the cans completely cover the chains. This arrangement assures that a steady stream of cans is available for the side delivery lugs or blocks 102 and 102', to subsequently deliver the articles or cans C forwardly in groups. As best shown in FIGURES 5 and 9, the cans C are delivered forwardly by the chains 426 to the point where the chains 100 and 100' engage the sprocket gears 101 and 101' whereat the lugs 102 and 102' separate each of the rows of cans into groups of threes and then deliver the cans C forwardly beyond the chains 426. As the cans C ride off of the chains 426 their ends slide upon the bars 430. From this point on the cans C are delivered by the lugs 102 and 102' to the article and carton converging station.

15 A guide chute broadly designated at 433 (FIGURE 20) is provided to keep the articles or cans in longitudinal alignment. The guide chute comprises a plurality of inverted U-shaped members 434 secured at their medial portions to vertical posts 435 which are in turn secured 20 to the longitudinal frame member 34 (FIGURE 9). The downwardly extending legs of the U-shaped members 434 have longitudinally extending rods or bars 434a and 434a' secured thereto as by welding.

25 The article delivery lugs 102 and 102' are moved longitudinally of the machine at a lower level than the bars 434a and 434a' and when the lugs are positioned on inner reaches of the chains 101, 101' in can engaging position they rest upon and slide along the longitudinal rods 436a and 436a' which are in alignment with the rods 30 434a and 434a'. The rods 436a and 436a' are secured to the top portion of vertical bars 436 and 436' which have their lower ends secured as by welding to the side frame members 427 and 427'. The lugs 102 and 102' (FIGURE 8) on the outer reaches of the chains 101, 101' 35 are slidably guided and supported in their path of travel by longitudinally extending plates 429, 429' suitably supported by arms 429a, 429a' secured to the side frame members 28, 28'.

Secured to the control bar 430 (FIGURE 20) of the article conveyor 150 is a longitudinally extending can separator plate 431. The can separator plate 431 holds the bottoms of opposing cans apart and a separator plate 437 fastened to the medial portion of the U-shaped members 434 extends longitudinally of the machine to separate 45 the tops of opposing cans. Again referring to FIGURE 9, it will be seen that the side frame members 427 and 427' terminate at a point approximately above the chime lock shaft 404 at which point a transverse frame 438 extends across the machine and is fastened to the side frame 50 members 28 and 28'. The longitudinal plate 428 and the longitudinal bars 430 extend forwardly from this point and terminate just short of the shaft 66.

Article and carton converging station

55 As best shown in FIGURES 9 and 11A, a carton blank B and the articles or cans C are delivered in timed relation to each other, the carton blanks B being moved upwardly by the blocks 372 on the carton delivery chains 67 and 67' and the cans C being delivered forwardly in 60 groups by the lugs 102, 102' on the can delivery chains 100 and 100'. Again referring to FIGURE 9, it will be seen that the articles or cans C are traveling in a straight line and that the carton blanks B are traveling forwardly and upwardly at an angle and that at a point approximately above the shaft 66, the foremost can C will be deposited upon the forward part of the carton blank B and when the rearmost edge of the carton blank is in vertical alignment with the center of the shaft 66, the carton blank will have received six cans thereon. At 65 this time the main conveyor 135 takes over and delivers the carton blank with its six cans thereon to the foremost part of the machine.

The main conveyor 135 comprises a sprocket chain 438 to which are fastened flat plate members 438a upon which the carton blanks B rest. Spaced blocks 439 are posi-

tioned on some of the plates 438a exactly one carton width apart to receive the carton blanks therebetween and prevent their shifting during their forward movement. In order that the main conveyor 135 can receive the carton blank and its cans thereon and move the same forwardly, one of the carton moving blocks 439 will be in vertical alinement above the shaft 66 with the lugs 372 and 372' of the carton blank delivery chains 67 and 67' to take over the forward movement of the carton blank therefrom. The can delivery lugs 102 and 102' are also timed to be in vertical alinement with the blocks 439, and the carton delivery lugs 372, 372' to effect the transfer of the cans onto the carton blanks without slowing down or stopping the forward movement of either the carton blanks or cans. As viewed in FIGURE 5, it is seen that the main delivery conveyor 135 will deliver the carton blank with cans thereon forwardly and at the same time the can delivery lugs 102 and 102' will ride out of engagement with the delivered cans.

In operation, the main conveyor 135 rides upon two longitudinal bars 525 and 525' (FIGURE 15) which rest upon side frame members 526 and 526' which are suitably secured to each other at their medial portions and are supported by channel members 527 and 527'. The channel members are positioned in the cut out portions 20a and 21a of the transverse plates 20 and 21, respectively, and are supported by the upper edges of the respective plates.

Carton gluing means

Referring to FIGURES 11a, 13 and 14, and more especially to FIGURE 11a, it will be seen that the sprocket gear 166 which is fixed on the shaft 440 will be turned in a clockwise direction the same as the shaft 51 from which it is driven by the chain 165. The shaft 440 extends through the gluing mechanism 170 and is journaled therein. Adjacent the sprocket gear 166 and keyed to the shaft 440 is a relatively large gear 442, which meshes with a smaller gear 443 disposed immediately above it, which in turn engages a small gear 444 immediately above it. To the right and left of the small gear 444 are gears 445 and 446, respectively, the gear 445 being mounted on a shaft 447 and the gear 446 being mounted on the shaft 448, which shafts 447 and 448 extend through the housing of the glue applying device and have knurled rollers 449 and 450 mounted on their outermost ends.

Suitably keyed to the innermost end of the shaft 440 is a glue applying wheel 451 whose lowermost portion is immersed in glue G provided in a container 452. The glue container 452 rests upon a plate 453, which plate with the glue container thereon can be manually lowered to facilitate replenishing the glue in the container. A manually operated hand wheel 454, positioned on the top of the gluing mechanism 170, is provided to move the knurled rollers 449 and 450 closer to and away from the glue applying wheel 451, to accommodate different thicknesses of carton material.

It will be seen from FIGURE 11a that the glue applying wheel 451 and gear 442 keyed to the shaft 440 would turn in a counterclockwise direction which would impart clockwise movement to the small gear 443 which, in turn, would provide counterclockwise movement to the small gear 444. The small gear 444 would then impart clockwise movement to both of the gears 445 and 446 and the knurled rollers 449 and 450 which engage one of the flaps of the carton blank. The primary purpose of the knurled rollers 449 and 450 is to maintain the bottom panel 394 of the carton blank B in engagement with the periphery of the glue applying wheel 451. Referring to FIGURES 11a and 13, it will be seen that adjacent the gluing apparatus 170, suitable carton guides or holding members in the form of a pair of spaced bars 455 are provided to insure that the bottom panel 394 of the carton blank B passes into engagement with the glue applying wheel 451.

Carton side folding means

Carton side folding members are provided to fold the carton blank into the position shown in FIGURE 30. These members are shown in the form of curved rods 457 and 457', the rearmost ends of which are fastened to the transverse plate member 20 at an elevation slightly lower than the main delivery conveyor 135. It will be observed that the rods 457 and 457' converge inwardly and upwardly and have their foremost ends fastened in upright brace members 460 and 460' which are mounted on longitudinal angle plates or bars 459 and 459' which extend between the transverse plates 20 and 21.

Means in the form of a flat bar with an upturned rearmost end 458 is provided to hold the cans down or against the carton blank top wall portion 385 while the side portions are being folded upwardly. The bar 458 (FIGURE 12) extends forwardly from a point underneath the transverse frame member 33 to a point corresponding to the station whereat the carton is finally assembled to encircle the group of cans. An inverted U-shaped member 464 has the foremost ends of the side guide rods 436a and 436a' secured thereto and has at its medial portion a post 462 extending downwardly, to which the rear portion of the article or can hold-down plate 458 is attached. A transverse brace 465 (FIGURE 15) is fastened between the longitudinal frame members 36 and 36' and serves to hold a vertical post 463 to which the front end of the can or article hold-down plate 458 is secured.

Carton bottom folding means

The carton blank B now partially assembled into the position shown in FIGURE 30 is moved forwardly by the main conveyor 135 to a point where the carton blank bottom wall sections 393 and 394 engage fold-down rods 470 and 471 (FIGURES 12 and 15). The rods 470 and 471 (FIGURES 5-A, 15 and 18) have their rearmost ends projecting outwardly from the center of the machine with their central portions converging downwardly at an angle to where their foremost ends are fastened to an angle bracket 472 which is secured to the rear end of the carton compression unit 142. The intermediate portions of the rods 470 and 471 are supported by vertical posts 473 and 473' from the transverse brace 465. It should be noted that the fold-down rod 471 has a greater curvature than the fold-down rod 470 to insure the bottom wall section 394 of the carton blank B being folded ahead of the bottom wall section 393 as shown in FIGURE 31. This order of folding is necessary since the glue G has already been applied to the surface of the bottom wall section 394 which is now facing upwardly and positioned underneath the overlapping portion of the corresponding bottom wall section 393.

Side pressure applying means

As the bottom wall sections 393 and 394 of the carton blank B are being folded downwardly into sealed position, the sides of the carton blank B then pass between two side pressure applying devices broadly designated at 480 and 480' (FIGURE 18). The pressure applying devices 480 and 480' are driven in timed relation with the movement of the main conveyor belt 135 and comprise the pairs of chains 116 and 116' having spaced guide lugs 481 and 481' thereon which engage the rear edges of the side portions of the carton blank B in alinement with the carton moving blocks 439 on the main conveyor 135. The fact that the spaced blocks 439 and the lugs 481 and 481' of the side compression units 480 and 480' are in alinement insures that the package is squared as it enters the compression station.

Chains 116 and 116' also have secured thereto small lugs 483 and 483', there being two lugs 483 and 483' spaced equidistant between the lugs 481 and 481'. The lugs 483, 483' grip the sides of the package at a point where the bottom wall flaps 393 and 394 have been folded inwardly away from the side wall portions 390 and 390',

or at the score lines 397 and 397'. The lugs 483 and 483' then force the side walls 390, 390' of the carton blank B into engagement and partially around the cans as they engage the sides of the carton blank B immediately between the articles or cans C and push the two bottom wall sections or panels 393 and 394 towards each other. The bottom panels 393 and 394 are then held together in overlapping relation by the lugs 483 and 483' until the package has passed underneath the main compression unit 142 at which time the glue G will set, securing the two bottom panels 393 and 394 together in slightly tensioned relation. The squeezing action of the lugs 483 and 483' on the sides of the assembled carton further helps to lock the articles or cans C therein by forcing the rim portions of the cans through the openings formed by the lip portions 392, 392', 398 and 398' in the carton side walls as clearly shown in FIGURES 24, 31 and 32 which positions the cans for being engaged by the carton chime locks 387 and 387'.

Overhead compression unit

The overhead compression unit broadly indicated by 142, as previously described, is driven by the sprocket 143 at the front of the machine, and comprises an endless belt having a resilient outer surface layer 490 (FIGURE 12) of sponge rubber or the like which is in turn secured to an internal belt 491, composed of rubber, leather or the like. The internal belt 491 has teeth 494 which mesh with the teeth of gears 493 and the drive sprocket 143 (FIGURE 6). Referring to FIGURE 6, it will be seen that the compression unit is provided with a framework made up of side panels 495 and 495' which are bridged at their uppermost edges by a longitudinally extending cover plate 496. Suitable carton side guides in the form of pairs of rods 530 and 530' are secured to the upright posts 35, 35' and 37, 37' in adjustable rod holding brackets 531 and 531'. The rods 530 and 531 guide the cartons and their contents throughout their forward movement through the side and overhead compression units.

The compression unit 142 is suspended above the main conveyor belt 135 for vertical adjustment, whereby the amount of pressure applied to the package can be varied. To accomplish this, vertically extending racks 500 and 501 (FIGURE 5A) are secured to the upright post 35 and 37, respectively and racks 500', 501' are fastened to the upright post 35' and 37'. Pinion gears 503 and 503' mesh with the racks 500 and 500' and are keyed on a transverse shaft 504 which is journaled in bearing brackets 505 and 505' carried by a transverse brace 506, which is fastened to the cover plate 496. Pinion gears 508, 508' mesh with the racks 501 and 501' and are keyed to a shaft 509 carried by bearing brackets 510 and 510' which, in turn, are mounted on a transverse brace 511, which is also secured to the cover plate 496, of the frame of the compression unit 142.

The shafts 504 and 509 have worm gears 512 and 513, respectively, keyed to their outermost ends. Worms 515 and 516 mesh with the tops of the worm gears 512 and 513 and are mounted on opposite ends of a common shaft 517 extending longitudinally of the machine which shaft is journaled in a bearing block 519 carried on the outermost end of the brace 506 and a bearing block 520 carried on the outermost end of the brace 511. Bearing block 520 is of the split housing type, and has a set screw 521 which, when tightened, locks the shaft 517, against rotation therein. A hand wheel 522 is provided adjacent the bearing block 519 as viewed in FIGURE 5A and by loosening the set screw 521, the shaft 517 can be rotated by the hand wheel 522 and the compression unit 142 can then be lowered or raised by the action of the pinion gears and racks heretofore described.

Electrical stop motion

Now, referring to FIGURE 25, it will be best understood how the machine is stopped in the absence of a sufficient supply of cans or carton blanks. Lead conductors 535 and 536, extend from a plug 538, which is adapted to be inserted into a source of electrical energy, not shown. A master switch 537 is interposed in the conductors 535 and 536 to provide manual cut off means for all of the electrical apparatus of the machine. A conductor 542 extends from the lead conductor 535 to one side of a normally open can controlled switch 544. A conductor 545, extends from the other side of the switch 544 to one side of a solenoid coil 546 and a conductor 543 connects the other side of the coil 546 to the lead conductor 536. A switch 544a is electrically arranged in series with the switch 544 by conductors 545a and 542a each having one of their ends connected to the switch 544a and their other ends connected to the conductors 545 and 542, respectively. The switches 544 and 544a are closed by articles or cans C being deposited on the article delivery conveyor 150, as shown best in FIGURE 20 wherein the switches extend upwardly through suitable openings provided in the longitudinally extending bars 430.

Whenever articles or cans C are on the conveyor 150, the switches 544 and 544a will be maintained closed and the solenoid coil 546 will then be energized to pull a solenoid plunger 547 upwardly, as shown in FIGURE 25. Suitably secured to the lower end of the plunger 547 and insulated therefrom is a rod 548 which has its opposite end fastened to a diaphragm 549, in a diaphragm housing broadly indicated at 550. Extending outwardly from each side of the rod 548, are arms 551 and 552. One end of a tension spring 553 is secured to the outer end of the arm 552 and the other end of the spring is fastened to the housing 550. The arm 551, when lowered with the plunger 547, opens a normally closed switch 555 interposed in a conductor 556 which leads from the conductor 542 to the main motor 40. A conductor 557 extends from the conductor 543 to a normally open switch 558, FIGURES 10, 11 and 25, which is positioned between the carton blank delivery chains 67 and 67' and is maintained closed by the carton blanks. To complete the circuit to the motor 40, a conductor 557a is connected to the opposite side of the normally open switch 558 and leads to the motor 40.

Whenever articles or cans C are exhausted from the delivery conveyor 150 above the switches 544 and 544a, the switches will be open to break the circuit to the coil 546, at which time the tension spring 553 will move the rod 548 and the solenoid plunger 547 downwardly. The rate of travel of the rod 548 is controlled by a valve regulating screw 560 which limits the amount of air escaping through a port 561 in the diaphragm housing 550. It is thus seen that the time can be accurately controlled when the arm 551 will engage and open the switch 555, to delay breaking the flow of electricity to the motor 40, to thereby stop the machine only after the cans in front of the switches 544 and 544a have been moved forwardly far enough to be engaged by the lugs 102 and 102' and moved to a point above the shaft 70 corresponding to the last carton blank needed to package the cans.

The normally open switch 553 is mounted to the side frame 427 of the conveyor 150 above the path of travel of the carton blanks B as they are delivered forwardly by the carton delivery chains 67 and 67' (FIGURE 11). The switch 558 has a follower 559 positioned on the end of a switch actuating lever 560, which when engaged by a carton blank B will close the switch 558. It should be noted that the follower 559 is of sufficient length to span the spacing between adjacent carton blanks. Therefore, upon successive cartons being delivered forwardly by the chains 67 and 67', the follower 559 will bridge

the gap between the successive cartons to thereby hold the switch 558 in closed position. If for any reason, a carton is not delivered by the vacuum feed cups 250, the switch 558 will open to instantly stop the flow of electricity to the motor 40, and thereby stop the machine.

As has already been described, the distance the cans or articles C will travel forwardly by the lugs 102 and 102' on the chains 100 and 100' driven by the motor 40 can be controlled by the manual screw 560 in the diaphragm housing 550. It is desirable in most cases, to have whatever articles, or cans C that remain on the article delivery conveyor 150 be moved forwardly on the machine, to the point approximately above and forwardly of the shaft 70. From this position above the shaft 70 to the forward end of the machine, the articles or cans C would have a carton blank B positioned therebeneath. Now, since the switch actuating arm 551 has opened the switch 555, the machine will be stopped.

In order to clear the machine of cans, it is desirable that the vacuum suction cups 250 do not deliver any more blank cartons B between the rollers 367, 367' and 355, 355', and to this end the manual switch a can be closed in the control panel 539 at which time the solenoid 329 will be energized to break the vacuum between the suction cups 250 and the vacuum pump 256. With the vacuum broken, and the switches 544, 544a and 555 open, conductors 570 and 571 are then utilized, to energize the motor 40. The conductors 570 and 571 extend to the lead conductors 535 and 536, respectively, with a switch d interposed in the line 570 which when closed, will energize the motor 40 to expel at the forward end of the machine whatever cartons and articles were left therein.

It is thus seen that there has been provided a machine for packaging cylindrical articles such as cans in a carton wherein both the articles and the cartons are continuously moved forwardly with the articles being delivered forwardly at one level while the carton blanks for forming the cartons are delivered upwardly and forwardly from below the articles to receive the articles thereon. There has also been provided novel means for punching and positioning the carton locking tabs to engage the rim or end portions of the cans to aid in retaining the cans in the completed package. There has also been provided means for applying glue to one of the carton flaps, means for folding the carton around a group of articles, and means for squaring and exerting a squeezing action on the sides of the carton to aid in positioning the rim portion of the articles therein within small apertures formed in the carton walls and wherein the latter means also serves to overlap the overlapping flaps a greater amount to permit the glue to set while the carton is in slightly tensioned condition to retain the end or rim portions of the articles in the carton apertures. To insure that the glue is set before the package is discharged from the machine, an overhead compression unit of a predetermined length is provided to exert a down pressure on the overlapping flaps.

In the drawings and specification there has been set forth a preferred embodiment of the invention and although specific terms are employed, they are used in a generic and descriptive sense only and not for purposes of limitation, the scope of the invention being defined in the claims.

We claim:

1. A method of packaging cylindrical cans in open-ended cartons while continuously moving the cans and cartons and wherein the cartons are formed from flat strip-like carton blanks each having a can receiving and supporting medial wall portion provided with aperture forming portions adjacent its opposite edges and having locking tabs provided with free ends formed integral therewith and positioned adjacent and in transverse alignment with the aperture forming portions; said method comprising feeding groups of cans forwardly in a sub-

stantially horizontal path of travel while supporting the cans in upright position on their lower ends, feeding the carton blanks in flat condition forwardly and upwardly in a path of travel in vertical alignment with the path of travel of the groups of cans to meet the cans at a predetermined point while moving the carton locking tabs into overlapping relation with the can receiving and supporting wall to position the free ends of the tabs to terminate substantially at the side edges of the wall adjacent the aperture forming portions, moving the groups of cans onto the medial wall portion of the carton blanks while moving the carton blanks forwardly in timed relation thereto and in substantially a horizontal path of travel, maintaining the carton blank aperture forming portions stationary while folding the opposite ends of the carton blanks upwardly into engagement with the sides of the cans thereon to form apertures, applying a squeezing inward pressure to opposite sides of the upturned carton blank portions to position rim portions of the cans in the carton blank apertures, folding inwardly in overlapping relation the opposite ends of the carton blanks while continuing to apply pressure to the opposite sides of the cartons, and adhesively securing the overlapping portions together while applying a downward pressure to the carton.

2. A machine for packaging cylindrical articles in cartons comprising means for continuously feeding cartons in flat strip-like blank form forwardly and upwardly from a stack in spaced apart relation comprising a suction device, means for moving the suction device in a vertical path of travel to lift a carton from the stack, means for moving the suction device forwardly in a substantially horizontal path of travel, feed rollers positioned adjacent the suction device to receive the cartons delivered thereto by the suction device, means for breaking the vacuum in the suction device simultaneously with the delivery of the cartons to the feed rollers, and inclined conveyor means for moving the cartons forwardly and upwardly from the feed rollers, means for feeding cylindrical articles forwardly onto the carton blanks in a substantially horizontal path of travel, means for applying adhesive to the cartons, means for continuously moving the cartons and articles thereon forwardly in substantially a horizontal path of travel, means for folding the cartons upwardly and around the articles and means for exerting a sealing pressure on the cartons to set the previously applied adhesive.

3. A machine for packaging cylindrical articles in cartons comprising means for continuously feeding cartons in flat strip-like blank form forwardly and upwardly from a stack in spaced apart relation, means for feeding cylindrical articles forwardly in a substantially horizontal path of travel onto the carton blanks, means for applying adhesive to the cartons, means for continuously moving the cartons and articles thereon forwardly in substantially a horizontal path of travel, means for folding the cartons upwardly and around the articles, and means for exerting a sealing pressure on the cartons to set the previously applied adhesive comprising a rotatable endless belt positioned above the path of travel of the cartons and adapted to engage the upper surface of the cartons and exert downward pressure thereon, and means for vertically adjusting the endless belt to vary the amount of pressure applied to the cartons comprising a framework for rotatably supporting the belt, a pair of spaced parallel shafts for supporting the framework, pairs of gears fixed on said shafts, vertically arranged racks provided with teeth for being engaged by said gears, worm gears on one end of said shafts, a worm shaft bridging said pair of shafts, worms provided on opposite ends of said worm shaft and being in engagement with said worm gears, means for adjustably locking said worm shaft, and handle means for rotating the shaft.

4. A machine for packaging cylindrical articles in cartons comprising means for continuously feeding cartons

in flat strip-like blank form forwardly and upwardly from a stack in spaced apart relation, means for feeding cylindrical articles forwardly in a substantially horizontal path of travel onto the carton blanks, means for applying adhesive to the cartons, means for continuously moving the cartons and articles thereon forwardly in substantially a horizontal path of travel, means for folding the cartons upwardly and around the articles, means for exerting a sealing pressure on the cartons to set the previously applied adhesive, and means for applying pressure to opposite sides of the cartons comprising a pair of oppositely rotating chains, said chains being provided with spaced lugs for engaging the sides of the cartons at a plurality of points in substantially lateral alignment with the points where adjacent articles in the cartons contact each other.

5. A machine for packaging cylindrical articles in cartons provided with articles locking tabs comprising means for continuously feeding cartons in flat strip-like blank form upwardly and forwardly from a stack in spaced apart relation, means for feeding cylindrical articles forwardly in a substantially horizontal path of travel onto the carton blanks, means for moving the carton locking tabs upwardly and outwardly in overlapping relation to its corresponding wall portion to engage the ends of articles positioned thereon comprising a pair of oscillatably mounted punch fingers positioned below the upward path of travel of the cartons, means for moving the fingers upwardly to engage and move the locking tabs upwardly in timed relation to the feed of the cartons, and longitudinally extending bars overlying the cartons and provided with angular edge portions to engage the upturned tabs and move them outwardly into overlapping relation to their corresponding walls, means for applying adhesive to the cartons, means for continuously moving the cartons and articles thereon forwardly in substantially a horizontal path of travel, means for folding the cartons upwardly and around the articles and means for exerting a sealing pressure on the cartons to set the previously applied adhesive.

6. A machine for forming cartons from flat substantially rectangular blanks and for placing articles in said cartons comprising means for successively conveying the cartons in blank form forwardly and upwardly into the machine one at a time to a predetermined point comprising a suction device, means for moving the suction device in a vertical path of travel to lift a carton blank from the top of a stack of carton blanks, means for moving the suction device forwardly in a substantially horizontal path of travel, feed rollers positioned adjacent the suction device to receive the carton blanks delivered thereto by the suction device, means for breaking the vacuum in the suction device simultaneously with the delivery of the carton blanks to the feed rollers, and inclined conveyor means for moving the cartons forwardly and upwardly from the feed rollers, means for moving articles into the machine and onto the carton blanks at said predetermined point, means for conveying the carton blanks and articles thereon forwardly in substantially a horizontal path of travel, means for folding spaced portions of each successive carton to form upwardly extending portions parallel to the articles, means for folding the upwardly extending carton portions inwardly over the articles in overlapping relation and means for securing the overlapping carton portions together.

7. A machine for forming cartons from flat substantially rectangular blanks and for placing articles in said cartons comprising means for successively conveying the cartons in blank form forwardly and upwardly into the machine one at a time to a predetermined point, means for moving articles into the machine and onto the carton blanks at said predetermined point, means for conveying the carton blanks and articles thereon forwardly in substantially a horizontal path of travel, means for folding spaced portions of each successive carton to form upwardly extending portions parallel to the articles, means

for folding the upwardly extending carton portions inwardly over the articles in overlapping relation, means for securing the overlapping carton portions together comprising a glue applying mechanism for applying an adhesive to one of the overlapping flaps, means for exerting a sealing pressure on the overlapping flaps comprising a rotatable endless belt positioned above the path of travel of the cartons and adapted to engage the upper surface of the cartons and exert a downward pressure, and means for vertically adjusting the endless belt to vary the amount of pressure applied to the cartons comprising a framework for rotatably supporting the belt, a pair of spaced parallel shafts for supporting said framework, pairs of gears fixed on said shafts, vertically arranged racks provided with teeth for being engaged by said gears, worm gears on one end of said shafts, a worm shaft bridging said pair of shafts, worms provided on opposite ends of said worm shaft and being in engagement with said worm gears, means for adjustably locking said worm shaft, and handle means for rotating the shaft.

8. A machine for forming cartons having locking tabs from flat substantially rectangular blanks and for placing articles in said cartons comprising means for successively conveying the cartons in blank form forwardly and upwardly into the machine one at a time to a predetermined point, means for moving articles into the machine and onto the carton blanks at said predetermined point, means for moving the carton locking tabs upwardly and outwardly in overlapping relation to its corresponding wall portion to engage the ends of articles positioned thereon comprising a pair of oscillatably mounted rod-like fingers positioned below the upward path of travel of the carton blanks, means for moving the fingers upwardly to engage and to move the locking tabs upwardly, and means for engaging the upturned locking tabs to fold the tabs outwardly in overlapping relation to their corresponding wall.

9. In a machine according to claim 8 wherein the means for engaging the upturned locking tabs comprises longitudinally extending bars overlying the carton blanks and

40 being provided with angular edge portions to engage the upturned tabs.

10. A machine for forming cartons from flat substantially rectangular blanks and for placing articles in said cartons comprising means for successively conveying the cartons in blank form forwardly and upwardly into the machine one at a time to a predetermined point, means for moving articles into the machine and onto the carton blanks at said predetermined point, means for conveying the carton blanks and articles thereon forwardly in substantially a horizontal path of travel, means for folding spaced portions of each successive carton to form upwardly extending portions parallel to the articles, means for folding the upwardly extending carton portions inwardly over the articles in overlapping relation, means for securing the overlapping carton portions together, and switch means connected in series and disposed in the path of travel of the articles and the carton blanks to stop the flow of the articles and carton blanks upon either becoming exhausted, said switch means disposed in the path of travel of the articles being provided with an adjustable delay switch to interrupt the feeding of the carton blanks only after sufficient carton blanks have been fed to accommodate the remaining articles.
